US0D1091208S

(12) **United States Design Patent** (10) **Patent No.:** **US D1,091,208 S**
(45) **Date of Patent:** **** Sep. 2, 2025**

(54) **BACK PAD**

(71) Applicant: **The Raymond Corporation**, Greene, NY (US)

(72) Inventors: **Daniel B. Miller**, Greene, NY (US); **Gregory W. Smiley**, Greene, NY (US); **Joseph T. Yahner**, Chenango Forks, NY (US); **Kurt R. Lutz**, Greene, NY (US); **Kurt R. Werner**, Auburn, NY (US); **Michael W. Konieczny**, Skaneateles, NY (US); **Frank J. Witkowski, III**, Syracuse, NY (US); **Howard Scott Ryan**, Skaneateles, NY (US)

(73) Assignee: **The Raymond Corporation**, Greene, NY (US)

(**) Term: **15 Years**

(21) Appl. No.: **29/842,186**

(22) Filed: **Jun. 10, 2022**

(51) LOC (15) Cl. **06-06**

(57) **CLAIM**

The ornamental design for a back pad, as shown and described.

DESCRIPTION

FIG. 1 is an isometric view of a top, front, and right side of an ornamental design for a back pad;

FIG. 2 is an isometric view of a bottom, front, and left side of the back pad of FIG. 1;

FIG. 3 is a front elevational view of the back pad of FIG. 1; FIG. 4 is a rear elevational view of the back pad of FIG. 1; FIG. 5 is a left side elevational view of the back pad of FIG. 1;

FIG. 6 is a right side elevational view of the back pad of FIG. 1;

FIG. 7 is a top plan view of the back pad of FIG. 1; and, FIG. 8 is a bottom plan view of the back pad of FIG. 1. In the drawings, the equal-length broken lines depict portions of the back pad that form no part of the claimed design.

1 Claim, 8 Drawing Sheets
